(57) **CLAIM**

The ornamental design for boot with legwarmer, as shown and described.

DESCRIPTION

FIG. 1 is a front perspective view of a first embodiment of the boot with legwarmer according to my invention;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a bottom elevation view thereof;

FIG. 7 is a front perspective view of a second embodiment of the boot with legwarmer according to my invention;

FIG. 8 is a left side elevation view thereof;

FIG. 9 is a front elevation view thereof;

FIG. 10 is a right side elevation view thereof;

FIG. 11 is a rear elevation view thereof; and,

FIG. 12 is a bottom elevation view thereof.

The dashed lines represent features forming no part of the design.
